BOILER

Michael C. Crotty, Flushing, N. Y.

Application November 29, 1946, Serial No. 712,847

7 Claims. (Cl. 122—136)

1

The present invention relates to boilers adapted to water heating and steam generation. While the invention is applicable to any boiler of this type, it is especially efficient in boilers of the Scotch marine type in that it is capable of producing hot water and steam with greater rapidity than is ordinarily the case even with this type of boiler.

As is well known, Scotch boilers are so constructed that the water of the boiler surrounds the combustion chamber of the furnace and thus has the advantage of contact of the water all around the directly heated surface of the combustion chamber. A constant steam pressure can thus be reliably secured and maintained rendering such boiler particularly desirable.

It is an object of the present invention to provide a boiler of the Scotch type that will develop a steam head with greater rapidity than has heretofore been possible.

It is a further object to adapt this type of boiler for use in homes and for industrial purposes where a quick supply of steam is of particular advantage.

It is a still further object to provide means for utilizing the gases of combustion for secondarily heating or superheating the water or steam after they have left the combustion chamber.

Briefly described, the boiler consists of a horizontal cylindrical fire box with the walls of the cylinder preferably corrugated to give greater heating surfaces. The fuel is preferably fuel oil or gas supplied by burners of known types discharging into the fire box or combustion chamber. A shell surrounds the fire box leaving a narrow space between the fire box wall and the shell into which water flows from the main boiler supply through holes at the bottom or under side of the shell. Pipes or risers at the top of the shell permit the water that has been heated within the shell to rise to the top of the boiler, thus drawing additional water into the shell through the holes at the bottom. A constant circulation is thus established and maintained. Means are further provided for conducting the hot gases of combustion from the fire box back and forth through flues passing through the boiler water in such a manner that the risers conveying the hot water from the shell to the top of the boiler are also further subjected to the heating action thereof by reason of the fact that these risers pass transversely of the flues and act as an interference to delay the passage of the gases of combustion.

In the drawings,

2

Fig. 1 is a sectional elevation of one form of the boiler taken along the line 1—1 of Fig. 2; Fig. 2 is a sectional elevation of the same boiler along the line 2—2 of Fig. 1.

5 The invention will be more clearly understood by reference to the drawings which represent a form of the device adapted for use in a building and in which 1 indicates the fire box or combustion chamber which, as seen from Fig. 2, is of a horizontal cylinder form, with corrugated sides.

Referring now to Fig. 1, a shell 2 surrounds the fire box 1. In the bottom or underside of the shell is an opening 3 through which water from the boiler 4 may enter the space 5 between

15 the fire box 1 and the shell 2. Water is fed to the boiler 4 through the intake 4a (Fig. 2). A burner 6, represented in the drawings (Fig. 2) as an oil burner, supplies heat to the fire box 1. Risers, two of which are indicated by the numerals 7 and 8 in Fig. 1 and more than two by cor-

20 responding numbers in Fig. 2, lead from the top of the shell to the upper part of the boiler 4, passing through the flues 9, 10 and 11. In flue 9 there is also located cross pipes 12 through which

25 water from the main boiler supply may pass, rising as it becomes heated; and similarly, in flue 10 similar pipes 13 function in the same manner. These risers, of which there may be more than shown in the drawings, depending on the size of the installation, and the short cross pipes indicated by numerals 12 and 13, which may also be more numerous than shown, permit an increase of rapidity of circulation within the boiler and, at the same time, act as baffles to the flow of the

30 35 hot gases of combustion, thereby obtaining a maximum heat therefrom before they pass to the stack or chimney.

The hot gases of combustion escape from the fire box 1 into the reversing chamber 14 and pass 40 upward and through the flues 9 and 10 to the smoke box 15 which is bolted on to the boiler 4 by the bolt and wing nut 16. The gases are thus again reversed and flow upwards and through flue 11. These hot gases thus pass over the

45 risers 7 and 8 in flues 9 and 10 and once again into the flue 11 over the same risers, and then pass through the outlet 17 of the flue 11 to the stack or chimney. If desired, pipes 18 connected

50 into the water lines of the house may be positioned in the upper part of the boiler and water for household purposes may be thus heated. The steam at the top of the boiler may be drawn off through the outlet 19 to the radiators or other apparatus.

55 The operation of the boiler is such that with

the main water supply within the boiler in contact with the heated surfaces of the fire box 1 within the shell 2, with the reversing chamber 14 and with the flues 9, 10 and 11, a very general heating of the main supply of water is effected, and furthermore the small supply of water between the shell 2 and the fire box 1 is rapidly heated and passed through the risers 7 and 8 where it is again subjected to the action of the hot gases within the flues 9, 10 and 11, after which it passes out to the top of the main water supply and is recirculated for further heating.

It will thus be evident that the hot gases of combustion are delayed in their passage through flues 9, 10 and 11 by the interruption effected by pipes or risers 7, 8, 12 and 13. As a result of this delay the gases remain longer in contact with the heating surfaces and thus give up more heat to the water passing through the risers and surrounding the flues.

It will be further understood that the flues may be greater in number than the three shown in the drawings, which are for purposes of illustration only. In fact, the number of flues may be greater or less depending on the size of the boiler installation. The flues, moreover, may be rectangular or circular in cross-section.

In the foregoing description, the invention has been described with particular reference to a Scotch type of boiler. It is within the contemplation of the invention, however, that the heating arrangements, including the combustion chamber, the reversing chamber, flues and smoke box, may be used with other types of furnace as, for instance, where a coal-burning open bottom combustion chamber is used. In this latter case the combustion chamber would not be entirely surrounded by the boiler water and the shell surrounding the combustion chamber, as shown, might be eliminated. The flues, however, would be traversed by short risers through which the heated boiler water would flow in the path of the hot combustion gases and would act to interfere with and baffle the flow of such gases, delaying the passage thereof until maximum heat was taken up by the water within said risers, in the same manner as hereinbefore described and illustrated in the drawings.

Having thus described my invention, what I claim is:

1. A boiler for water heating and steam generation comprising within said boiler a combustion chamber surrounded by a shell spaced a short distance therefrom, said shell having openings at the bottom thereof to admit water from the main boiler supply to the space between said combustion chamber and said shell; flues traversing the water in said boiler and communicating with said combustion chamber and adapted and arranged to conduct hot gases of combustion back and forth through said boiler; and risers connected with the top of said shell and passing upward through said boiler water and traversing said flues to the upper part of said boiler, said risers being so positioned within said flues that they obstruct and delay the flow of hot gases, thereby conducting water heated between said shell and said combustion chamber to be further heated within said flues.

2. A boiler for water heating and steam generation comprising a combustion chamber entirely surrounded by water in said boiler; a shell surrounding said combustion chamber and itself surrounded by water in said boiler, thus forming a small compartment between the walls of said

combustion chamber and said shell; openings in the bottom of said shell to admit water from said boiler supply to said compartment and risers at the top of said shell adapted and arranged to conduct water heated in said compartment to the upper part of said boiler water supply; and flues communicating with said combustion chamber and traversing said boiler water supply and being traversed by said risers, whereby said hot gases of combustion are delayed in their flow through said flues and caused to yield the greater portion of their heat to the water in said boiler and in said risers before escaping to the stack.

3. A boiler of the Scotch marine type comprising a combustion chamber, a shell spaced from said combustion chamber and completely surrounding the same, openings at the bottom of said shell to admit boiler water to the space between said shell and the walls of said combustion chamber, and risers leading from the top of said shell to the upper part of said boiler; flues communicating with said combustion chamber, traversing said boiler and being traversed by said risers and being adapted and arranged to conduct hot gases of combustion back and forth through said boiler, thereby providing hot surfaces in contact with the main boiler water supply and further heating the water in said risers passing through said flues, said risers being so positioned in the path of said flue gases as to delay the flow thereof and to cause them to yield maximum heat before escaping to the stack.

4. A Scotch marine type boiler comprising a heating system including a combustion chamber, flues communicating therewith and traversing said boiler, said flues being adapted and arranged to conduct hot gases from said combustion chamber back and forth through said boiler to a stack; a shell surrounding said combustion chamber and spaced therefrom; a water supply in said boiler in contact with the outside surfaces of said shell and said flues; means to admit small quantities of boiler water to fill the space between said shell and the wall of said combustion chamber and riser means at the top of said shell to conduct water heated in said space for further heating through said flues and thence to the top of said boiler.

5. A boiler for water heating and steam generation comprising an outer chamber containing water, a combustion chamber horizontally disposed within said outer chamber and surrounded by a shell spaced from said combustion chamber; means for admitting water from said outer chamber to the space between said combustion chamber and said shell and pipe means to conduct hot water and steam from the top of said shell to the upper part of said water in said outer chamber; and flues associated with said combustion chamber and traversing the water in said outer chamber back and forth, said flues being traversed by said pipe means for conducting water.

6. A boiler for water heating and steam generation comprising a boiler chamber containing water, a combustion chamber, a shell spaced from and surrounding said combustion chamber adapted and arranged to admit boiler water to the space between said shell and said combustion chamber, a system of flues communicating with said combustion chamber and traversing the water in said boiler above said combustion chamber and a system of tubes communicating with said shell and traversing said flues, whereby hot gases of combustion are conducted by said flues from said combustion chamber back and forth through

said boiler water and whereby heated boiler water flows through said tubes traversing the path of said hot gases passing through said flues.

7. A boiler for heating water and generating steam comprising a combustion chamber positioned within a boiler compartment containing a water supply, a shell surrounding said combustion chamber and spaced therefrom, means for admitting boiler water to the space between said shell and said combustion chamber, flue means for 10 directing the hot gases of combustion from said combustion chamber back and forth of said boiler water above said combustion chamber and tube

means traversing said flues directing said boiler water from said shell across the path of said hot gases in said flues.
